Primary Examiner — Mitchell I. Siegel

(57) **CLAIM**

The ornamental design for a golf club head, as shown and described herein.

DESCRIPTION

FIG. 1 is a front isometric view of a golf club head showing my new design;

FIG. 2 is a front elevational view of the golf club head of FIG. 1;

FIG. 3 is a rear elevational view of the golf club head of FIG. 1;

FIG. 4 is a right side elevational view of the golf club head of FIG. 1;

FIG. 5 is left side elevational view of the golf club head of FIG. 1;

FIG. 6 is top plan view of the golf club head of FIG. 1;

FIG. 7 is a bottom plan view of the golf club head of FIG. 1;

FIG. 8 is a cross-sectional view taken on line 8-8 of FIG. 3;

FIG. 9 is a perspective view of the golf club head of FIG. 1; and,

FIG. 10 is a perspective view of the golf club head of FIG. 1.

The features shown in broken lines in the drawing depict portions of the design that form no part of the claimed design.
